United States Patent Office.

ALFRED S. DICKINSON, OF NEW YORK, N. Y.

Letters Patent No. 95,993, dated October 19, 1869.

IMPROVED CURTAIN-FIXTURE.

The Schedule referred to in these Letters Patent and making part of the same.

To all whom it may concern:

Be it known that I, ALFRED S. DICKINSON, of the city, county, and State of New York, have invented a new and useful Curtain-Fixture; and I do hereby declare that the following is a full, clear, and exact description thereof, reference being had to the annexed drawings; making part of this specification, in which—

Figure 1 is a front elevation,

Figure 2, a side elevation, and

Figures 3, 4, 5, and 6, are different views of the semicircular glass sheave.

Like letters denote like parts in the several figures.

My invention relates to curtain-fixtures; and

It consists in the combination of an open frame, and one or more semicircular glass sheaves fixed therein, over which the cords are to be passed for operating the curtain.

To enable those skilled in the art to make and use my invention, I will proceed to describe its construction and operation.

In the drawings—

A represents the frame, which may be made of sheet-metal. It is to be formed as shown in figs. 1 and 2, its base being of the necessary dimensions to receive the sheave or sheaves, which are to rest upon it, and which are to be held between the sides, which rise from the base vertically for some distance, and are then made to approach each other, when they again rise vertically to their termination.

The upper ends of the sides are perforated, so that the frame may be attached to the window-sash, which may be done by screwing it thereto, or by hanging it on a stud, as preferred.

B represents the semicircular sheave, which is to be made of glass, porcelain, or other such like material.

The length of the base of this sheave is such, that when it is inserted in the frame A, it projects on either side thereof, and such projecting parts have spurs b, formed on each side, between which the sides of the frame fit snugly.

The sheave is to have a rounded groove formed in its edge, for guiding a cord in the usual manner.

I have shown the base of the sheave as flat; but it may have formed upon it spurs or points, in which case the base of the frame is to be provided with corresponding perforations, into which the points of the sheave recede, thus giving it more steadiness.

The thickness of the sheave is such, that when inserted in the frame, which is done by springing the sides apart a little, and pushing one end of the sheave through, it is firmly held between its sides, its spurs preventing it from slipping out.

I have shown but a single sheave; but it is apparent that two or more may be held in the same frame, it only being necessary to enlarge the capacity of the latter.

Having thus described my invention,

What I claim, and desire to secure by Letters Patent, is—

A curtain-fixture, combining in its construction a frame, A, and one or more semicircular glass sheaves, B, constructed and arranged, in relation to each other, as shown and described.

In testimony whereof, I have signed my name to this specification, in the presence of two subscribing witnesses.

ALFRED S. DICKINSON.
